REFINING PRESSURE TAR

Robert E. Wilson, Chicago, Ill., assignor to Standard Oil Company, Chicago, Ill., a corporation of Indiana

Application July 5, 1932, Serial No. 620,838

3 Claims. (Cl. 196—13)

This invention relates to a process of refining pressure tar and more particularly to a method and means for utilizing the pressure tar from cracking operations.

5 In the production of cracked gasoline, mineral oils of various types are heated to about 750° to 1000° F., at pressures of about 100 to 1000 pounds per square inch, and the reaction products are maintained under pressure at elevated temperatures for a sufficient period to convert the oils into light hydrocarbons, such as gasoline and heavy hydrocarbons, which are generally called pressure tar. The utilization of pressure tar is a problem which has confronted petroleum refiners 10 since the beginning of the cracking industry. This tar has heretofore been used as a cheap fuel or road surfacing material, and much of this oil has not been entirely satisfactory even for these uses.

20 The object of my invention is to provide a means for converting this type of material into more valuable products; particularly to recover clean oil of high heating value for use as a fuel or for use as a cracking or hydrogenation stock.

25 A further object is to prepare from this tar an improved road oil characterized by a high hexane insoluble content. Other objects will be apparent from the following detailed description.

In practicing my invention I separate the tar 30 into two fractions each of which is more valuable than the original material. I treat the tar with a solvent for separating the asphalt from paraffinic and naphthenic oils, preferably using a liquefied normally gaseous light hydrocarbon, such as propane. I have found that propane will precipitate about half of the reduced pressure tar as asphalt. The remaining half is an oily liquid of red or brown color closely resembling lubricating oils of intermediate viscosity (about 35 300 seconds Saybolt at 100° F.) and having a high density (about 12° A. P. I.), a high vapor pressure and a low boiling point. This oily liquid is suitable for lubricating purposes where high volatility is desired, as with Diesel engines.

40 It is particularly valuable as a charging stock for cracking and hydrogenation processes where it yields a motor fuel of unusually high knock-rating characteristics. Gasoline prepared from this stock will have a knock-rating of 75 octane number or higher, and may be marketed as a premium motor fuel.

The asphalt which is precipitated by the propane is characterized by a very high hexane insoluble content and it may be blended with road oils to increase their hexane insoluble content

and to improve their characteristics generally. The precipitation of asphalt from pressure tar by propane gives a product which, in many respects, resembles high melting asphalt and it may therefore be applied to new uses, particularly 5 in the fields of weather proofing, insulating, roofing, etc.

The invention will be more clearly understood from the following description and from the accompanying drawing which forms a part of this 10 specification and in which I have diagrammatically illustrated a plan of my improved refining system.

Although the invention is particularly directed to the utilization of pressure tars from liquid 15 phase cracking processes, it should be understood that it is equally applicable to tars from vapor phase processes operating at low pressures. In my preferred example I will describe a pressure tar from a Holmes-Manley cracking unit 20 operated at about 900° F. under a pressure of about 300 pounds per square inch.

The pressure tar from this cracking unit is flashed (distilled by its contained heat) at atmospheric pressure to yield a reduced pressure 25 tar having a furol viscosity at 122° F. of about 125. This tar has a hexane insoluble content of only about 8% to 10%.

This reduced pressure tar at about 400° to 500° F. is introduced into the system through line 10, 30 passed through coil 11 in asphalt still 12, and thence through cooler 13 to mixer 14 wherein it is thoroughly mixed with propane from storage tank 15, pipe 16, pump 17 and pipe 18 or used propane from pipe 19. The mixture is preferably 35 at a temperature of about 150° to 100° F., and I may use about four or five volumes of propane per volume of pressure tar. If desired, I may conduct the separation with propane at still lower 40 temperatures, for example I may operate at a temperature of about 50 to 100° F. It should be understood that impure propane, ethane, isobutane, butane, etc., and/or mixtures thereof, may be used in the place of pure propane. Also 45 the proportions of propane to pressure tar may be varied through a relatively wide range depending upon the degree of separation required, the amount of oil to be removed from the pressure tar, the type of apparatus used, etc.

The mixture of pressure tar and propane, preferably at about 150° to 100° F. is introduced through pipe 20 and valve 21 into settling chamber 22, the temperature of which may be controlled by the vaporization of a part of the propane, vapors being removed through pipe 23 55

and compressor 24, or by-pass 25 to condenser 26 and storage tank 15. The asphalt precipitates rapidly even at high temperatures and may be withdrawn from the bottom of the settler 5 through conduit 21 by conveyor 28 and introduced into the asphalt still 12 wherein propane is removed. Instead of settling, I may filter the precipitated asphalt, especially when large amounts of propane are used. The finished 10 asphalt is withdrawn through pipe 29 to storage tank 30 and the propane is conducted under high pressure through pipe 31 to condenser 32, wherein it is liquefied and returned to storage tank 15.

15 The upper liquid layer in the settling chamber 22 consists of propane and dissolved oil and it may be transferred from settling chamber 22 through pipe 33, pump 34, and pipe 19 back to the inlet of the mixer; when a relatively small amount of oil is 20 to be removed from the pressure tar, the propane may thus be recycled for a considerable length of time. However, in my preferred embodiment I withdraw the propane solution through pipes 36 and 37 to tower 38, which is heated by steam or 25 hot water in coil 39, separated oil being withdrawn through pipe 40 and propane vapors being returned through pipe 41 to condenser 42 and propane storage tank 15. Alternatively the propane may be removed by flashing under reduced pressure. The oil which is removed through pipe 40 is 30 substantially asphalt free, it is clean, it has an exceptionally high heat content, and it makes an excellent burning oil. Furthermore, it may, if desired, be used as a charging stock for making further amounts of cracked gasoline or as a 35 hydrogenation stock.

In some instances it may be desired to separate wax or other impurities which might be present in an asphaltic residuum and which might not be 40 separated in settling chamber 22 at high temperatures. In such cases I pass the propane solution from the top of settling chamber 22 through reducing valve 43 to a second settling chamber 44 which is cooled by external means and/or maintained at low temperature by the removal of 45 propane gases through pipe 45 and pump 46 or by-pass 47 to condenser 26 and storage tank 15. In settling chamber 44 I may obtain temperatures as low as -30° F., -50° F., or at even lower 50 temperatures when hydrocarbons lower than propane alone are used. At this temperature I may separate a considerable amount of waxy or asphaltic substances which were not removed in settling chamber 22. The precipitated substances may be 55 withdrawn through conveyor 48 to boiler 49 wherein the propane is removed by heater 50 and conducted by pipe 51 back to a suitable condenser and to storage tank 15. The finished material, which will be an asphalt of a different character from that obtained in stripper 12, may be 60 withdrawn through pipe 52 and stored in tank 53. The propane solution from the second chiller may be transferred by pipe 54 to boiler 38 and the propane may be removed therefrom as 65 hereinabove described.

If additional propane is required for the chilling operations or for washing or further dilution, it may be supplied to either settling chamber 22 or 44 directly from storage tank 15 through pipes 55 and 56 or 57. The system may be operated either batchwise or continuously, and when it is operated batchwise the propane solution may be transferred by pipe 58 to reboiler 38 after the asphalt has been removed from the settling 70 chamber.

It will be obvious, of course, that all of the above equipment must be designed to withstand high pressures and should preferably be well insulated. Various connections, operating valves, safety valves, etc. may be used in accordance with 5 ordinary engineering practice. Other washing steps, countercurrent extraction steps and asphalt separation under widely varying temperature conditions are contemplated. In some cases it may be necessary or advisable to melt or dissolve the precipitated asphalt to facilitate its transfer from one part of the system to another,—one skilled in the art will use heaters where necessary, steam jacketed pipes, etc., or he will add diluents or solvents as the occasion may 10 demand.

I have found that the recovered asphalt has new and valuable properties and that it may be used in many new fields, particularly in the fields of roofing material, insulation, weather proofing, etc. 20 I have also found that the asphalt from storage tank 30 may be blended in small amounts with road oils to markedly increase their hexane insoluble content, and to otherwise improve their character. The method of determining the hexane insoluble content of a road oil is described as Test 23 in Abraham "Asphalts and Allied Substances" (Van Nostrand 1929, page 724). I have found that the asphalt precipitated from pressure tar, as hereinabove described, may contain upwards of 30% hexane insoluble matted—appreciably greater amounts of hexane insoluble substances than contained in the original pressure tar. It appears, therefore, that the hexane insoluble substances are not merely concentrated 35 but are even increased. The blending of this asphalt with reduced pressure tar yields an excellent road oil.

While I have described the use of propane as a normally gaseous diluent, it should be understood 40 that any solvent may be used which has the property of separating the components of the pressure tar as hereinabove described. A normally gaseous light hydrocarbon, such as propane, ethane, butane, ethylene, etc. is particularly useful for this purpose, but substituted hydrocarbons or other organic solvents having high precipitating power for these asphaltic materials may likewise be used.

I have described in detail a preferred embodiment of my invention, but it should be understood that this is by way of example only and that I do not limit myself to such details except as defined by the following claims, which should be construed as broadly as the prior art will permit. 55

I claim:

1. The method of increasing the hexane insoluble content of road oil derived from pressure tar from cracking operations which comprises mixing said pressure tar with a liquefied normally gaseous hydrocarbon consisting essentially of hydrocarbons containing 2 to 4 carbon atoms at a temperature of about 100 to 150° F. and under a pressure sufficient to maintain said hydrocarbons in liquid phase, separating the resulting mixture 60 into a portion soluble in said hydrocarbons and a portion insoluble in said hydrocarbons, recovering said insoluble portion and blending it with a blending oil derived from pressure tar to produce an improved road oil having a higher content of material insoluble in hexane than that of the original pressure tar or said blending oil.

2. The method in accordance with claim 1 wherein the normally gaseous hydrocarbon is propane.

3. The method of increasing the hexane insoluble content of road oil derived from pressure tar from cracking operations which comprises mixing said pressure tar with a liquefied normally gaseous hydrocarbon consisting essentially of hydrocarbons containing 2 to 4 carbon atoms at a temperature of about 50 to 150° F. and under a pressure sufficient to maintain said hydrocarbons in liquid phase, separating the resulting mixture

into a portion soluble in said hydrocarbons and a portion insoluble in said hydrocarbons, recovering said insoluble portion and blending it with a blending oil derived from pressure tar to produce an improved road oil having a higher content of material insoluble in hexane than that of the original pressure tar or said blending oil.

ROBERT E. WILSON.
